INTERFACE MONITOR

Renato A. D'Antonio, North Attleboro, Mass, assignor to
International Data Sciences, Inc.

Filed June 9, 1975, Ser. No. 585,335

Term of patent 14 years

Int. Cl. D10—04

U.S. Cl. D10—46

FIG. 1

FIG. 2

FIG. 3

FIG. 4

FIG. 5

FIG. 6

FIG. 1 is a front elevational view of an interface monitor showing my new design:

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof.

The wire leads are shown broken away in FIGS. 1-4 to indicate indeterminate length.

I claim:

The ornamental design for an interface monitor, substantially as shown and described.
